CIRCUIT INTERRUPTER AND METHOD OF MAKING THE SAME

Robert C. Dickinson and Russell E. Frink, Pittsburgh, Pa.,
assignors to Westinghouse Electric Corporation, East
Pittsburgh, Pa., a corporation of Pennsylvania

Application November 28, 1952, Serial No. 323,010

8 Claims. (Cl. 200—144)

This invention relates to circuit interrupters in general, and, more particularly, to arc-extinguishing structures therefor and a method of making the same.

A general object of our invention is to provide an improved arc-chute construction involving a pair of spaced side-wall members cooperating to provide an improved arc chute of the spaced slotted plate type.

A further object of our invention is to provide an improved process or method of manufacturing arc-chute side-wall members of the foregoing type.

Further objects and advantages will readily become apparent upon reading the following specification, taken in conjunction with the drawings, in which

Figure 1 is a side elevational view, partially in vertical section, showing a circuit interrupter embodying our invention, the contact structure being shown in the closed-circuit position;

Fig. 2 is a fragmentary, vertical sectional view taken along the line II—II of Fig. 1;

Fig. 3 is a sectional view through one of our finished, insulating, side-wall members;

Fig. 4 is a fragmentary top plan view of the finished insulating, side-wall member of Fig. 3;

Fig. 5 is a fragmentary view looking at the other, or lower, end of the side-wall member of Fig. 3;

Fig. 6 is a fragmentary, sectional view taken substantially along the line VI—VI of Fig. 2;

Fig. 7 is a fragmentary, lower-end view of the insulating blank used in forming one of our finished, insulating side-wall members; and

Fig. 8 is a fragmentary view, partially in section, showing the cutting operation being performed upon a blank such as shown in Fig. 7.

Referring to the drawings, and more particularly to Fig. 1 thereof, the reference numeral 1 generally designates suitable contact structure which, when separated to the open-circuit position, establishes an arc which is moved upwardly into an arc chute, generally designated by the reference numeral 2 as a result of the transverse magnetic field set up by the blowout coil 3 and associated magnet structure 4. A rotatable contact arm 5 carries a conducting bridge 6, which, in the closed-circuit position, as shown in Fig. 1, interconnects stationary main contacts 7, 8.

A contact stud 9 carries the current from the stationary main contact 7, through an insulating bushing 10 to the external circuit. The contact stud for the stationary main contact 8 is not shown, but it may be identical to the contact stud 9.

Consequently, in the closed-circuit position of the interrupter, as shown in Fig. 1, the electrical circuit comprises the contact stud 9, stationary main contact 7, conducting bridge 6, stationary main contact 8, to the contact stud therefor, not shown, to the external circuit.

During the opening operation of the interrupter, the contact arm 5 is rotated in a clockwise direction about a pivot pin, not shown, but which is in electrical contact

with the stationary main contact 8, to draw an arc between the arcing contacts 11, 12 after the separation of conducting bridge 6 from the main contacts 7, 8.

When the arcing contacts 11, 12 separate, the arc formed therebetween will expand upwardly because of the loop circuit so that one terminal thereof will be transferred to the arc terminal member 18, and the other arc terminal will be transferred to the other arc terminal member 19.

When this occurs, the blowout coil 3 will be put into series circuit, and the transverse magnetic field set up thereby between the field pole members 14 (Fig. 2) will move the established arc upwardly along the arc terminal members 18, 19 into the arc chute 2. The electrical circuit now comprises contact stud 9, conductor 20, blowout coil 3, contact clip 15, arc terminal member 18, the arc itself, arc terminal member 19, flexible shunt 28, contact arm 5 to the other contact stud, not shown.

The arc chute 2 comprises an insulating rectangularly-shaped housing member 22 positioned adjacent to an insulating plate 21, the latter serving as a base for the blowout coil 3. Within the housing 22 is placed a pair of mating or cooperating identical insulating spaced side-wall members 23, 24. Fig. 3 shows a sectional view through one of the insulating side-wall members 24. It will be noted that the side-wall member 24 has a side-wall portion 24a, and a plurality of primary ridges 24b. Preferably, each primary ridge 24b has an offset portion 24c, the purpose for which will be more apparent hereinafter. Disposed between adjacent primary ridges 24b are a plurality of secondary ridges 24d, the configuration of which is more clearly apparent from an inspection of Figs. 4 and 5 of the drawings.

Thus, upon assembling the two side-wall members 23, 24, the offset portions 24c of the side-wall member 24 engage the side-wall portion 23a of the side-wall member 23. Also, the secondary ridges 24d of the side-wall member 24 cooperate with the primary ridges 23b of the side-wall member 23, in a manner more clearly shown in Fig. 2 of the drawings.

It will be noted that the primary ridges of one side-wall member are in substantially the same plane as the secondary ridges of the other side-wall member, so that the effect of assembling two of the side-wall members 23, 24 results essentially in a spaced-slotted-plate construction, as more clearly shown in Figs. 2 and 6 of the drawings.

We are well aware of prior-art constructions involving such an interleaving ridge arrangement, such as shown in U. S. Patent 2,417,683, issued March 18, 1947, to Winton G. Harlow. Such a prior-art arc chute has the primary ridges themselves engaging the opposite side-wall member, so that the arc is compelled to contact the opposite side-wall member. However, in our construction, as shown in Fig. 6, the arc, indicated by the dotted line

55 25, never reaches the side-wall portions 23a, 24a, but is cooled and deionized by the cool surfaces and the cool fluid contained within the notches 26, provided between primary and secondary ridges extending from the same wall member. These notches or pockets 26 provide cool surfaces and a quantity of un-ionized gas which cools the arc 25 and brings about its rapid extinction. Moreover, our improved construction, unlike the prior-art arrangements, does not permit the arc to move along the outer edge of the primary ridges near the exhaust end of the arc chute. As indicated in Figs. 2 and 3, the arc 25 moves up to the point A, where it is stopped by the solid insulating material forming the offset ridge portion 23c or 24c. Hence, the arc 25 is effectively trapped at this point A, and has no tendency to wear its way along to the exhaust end of the arc chute 2.

Fig. 7 indicates how a blank side-wall member is con-

figured. As shown, there are provided deep and shallow valleys 31, 32 in the blanking operation. Thus, Fig. 7 shows a fragmentary lower-end view of a blank, in which the shallow valley 32 is bounded or defined by the sides of the unfinished ridges 33 and by the tops of the unfinished secondary ridges. As shown in Fig. 8, by employing a gang of spaced cutters 36, separated by spacers 37, 37a and arranged for simultaneous actuation on the same cutter shaft 38, the blank of Fig. 7 may be run through against the cutter gang, to result in the cutters 36, finishing the sides of the primary ridges 24b and cutting out the secondary ridges 24d in the same operation.

From the foregoing, it will be observed that assuming that the blank is run through the cutters from the exhaust end B thereof (Fig. 3) that first the cutters 36 cut away portions of the ridges 33, making the sides thereof parallel, as indicated in Fig. 4, to finish the primary ridges 23b, 24b. When the cutters 36 arrive at the point C (Fig. 3) they cut away the notches or slots 26, more clearly shown in Fig. 6 of the drawings. Thus by one sweep of the arc-chute side-wall blank 35 through the gang of cutters, the finished side-wall member 23, 24 is formed.

From the foregoing it will be apparent that we have described an interrupter assembly particularly adapted for magnetic air-type circuit breakers, the chief advantage of which is simplified manufacture. Interrupters of this type at present are made from flat ceramic plates. For example, for a rating of 4.16/4.76 kv. and 250,000 kva., these plates are $2\frac{1}{4}$ inches by 12 inches by $\frac{3}{16}$ inch thick, 32 plates being used for each single pole assembly. These plates are made with an offset V-shaped notch extending inwardly for 7 inches from one of the narrow ends. Reference may be had to U. S. Patent 2,442,199 issued May 25, 1948, to Robert C. Dickinson and Russell E. Frink and assigned to the assignee of the instant application. The plates are stacked with cemented asbestos-rope spacers between the long edges, and with the offset of the notches placed alternately to the right and left of the center-line. Spacers of accurate thickness are placed between the plates, and the assembly is clamped together and baked so as to set up the cement. The spacers are then removed. In order to preserve the shape of the plates during firing, the plates are pressed with a tie across the open end of the notch. After firing, the ties must be cut off.

The structure of our invention has several advantages over interrupters made previously by methods somewhat similar to this. In the previous constructions, so far as we are aware, the secondary ridges 24d, 23d had not been used, the primary ridges 23b, 24b projecting in a smooth curve close to the opposite side-wall member but not meeting it. In this type of a structure, the arc can go completely through the interrupter and continue to burn over the other end. In order to prevent this, an expensive muffler must be provided. This muffler generates back-pressure and impedes the progress of the arc; the theory being that if the arc moves slowly enough, interruption will occur before the arc has gone completely through the interrupter. On the other hand, in the structure according to our invention, the arc 25 will be driven up into the notches 29 formed between the outer edges of the primary ridges 23b, 24b and the sides of the secondary ridges 23d, 24d, but will not go beyond the point A of Figs. 2 and 3, since arc travel beyond this point A would represent a large and abrupt increase in arc energy. This permits making the exhaust passages 30 (Fig. 6) through the interrupter much freer, bringing magnetic deionization into play. The theory of magnetic deionization has been thoroughly covered in Ludwig Patent No. 2,243,038, and briefly consists of magnetically driving ions out of the arc 25. This force is transmitted to the gas surrounding the arc in collisions between the ions and the neutral gas molecules. Thus, the moving ions cause un-ionized gas to be placed in motion so that a new supply of cool un-ionized gas is constantly being

drawn past the arc. If the structure is open through, as in previous designs, in which primary ridges come close to, but never reach, the opposite wall member, the arc moves along with the air blast and advantage cannot be taken of this method of deionization.

In another type of construction, as set out in Patent No. 2,417,683, the secondary ridges employed in our invention are not used and the curve of the primary ridges extends over completely to the opposite side-wall member. While this construction is somewhat superior to the open construction, in respect to keeping the arc inside the interrupter, there is a crack along the joint between the primary ridges and the opposite side wall member, which the arc will erode out and make it even-tually like the open structure.

In the latter construction, the arc comes into contact with ceramic surfaces and heats them to a very high temperature so that they tend to become conducting. In our construction, it will be observed that by each joint where the direction of the arc 25 is reversed, as shown in Fig. 6, there is a surface bounding the notches 26 which does not come in direct contact with the arc 25. These surfaces will therefore remain much cooler and will retain their dielectric strength. If the secondary ridges 23d, 24d are not used, the arc will be against a continuous ceramic surface throughout its length, which will be uniformly heated; and the dielectric strength will be much lower than where these relatively cooler surfaces, forming the notches 26 (Fig. 6), are interposed.

We have also disclosed a method for manufacture of the device, which consists of two identical pieces. The blank 35 is dry-pressed as shown in Fig. 7, and after it is cured, it is machined with a gang of circuit cutters 36, which removes material from between each of the unfinished primary ridges 33. The milling might be done before or after firing the piece 35. While the structure, as described, may be made of a fired ceramic porcelain, it could be made from any suitable material for interrupters of this type, such as cold-molded asbestos-Portland-cement mixtures, etc.

Although we have shown and described a specific structure, and a method or process for forming the same, it is to be clearly understood that the same were merely for the purpose of illustration, and that changes and modifications may readily be made by those skilled in the art, without departing from the spirit and scope of the invention.

We claim as our invention:

1. A circuit interrupter including relatively movable contacts between which an arc may be formed upon opening the circuit, an insulating arc chute in which the arc is moved including spaced side wall members, each side wall member having on its side facing the other side wall member a plurality of primary ridges extending longitudinally in the general direction of movement of said arc through said chute, at least some of the primary ridges having offset portions to engage the opposite wall, and a plurality of cooperating secondary ridges in the same general plane as the said some primary ridges extending inwardly from the opposite side wall member.

2. A circuit interrupter including relatively movable contacts between which an arc may be formed upon opening the circuit, an insulating arc chute in which the arc is moved including spaced side wall members, each side wall member having on its side facing the other side wall member a plurality of primary ridges extending longitudinally in the general direction of movement of said arc through said chute, at least some of the primary ridges having offset portions to engage the opposite wall, a plurality of cooperating relatively short secondary ridges in the same general plane as the said some primary ridges extending inwardly from the opposite side wall member, and the offset portions extending over and engaging the secondary ridges to form a generally slotted plate construction.

3. A circuit interrupter including relatively movable contacts between which an arc may be formed upon opening the circuit, an insulating arc chute in which the arc is moved including spaced side wall members, each side wall member having on its side facing the other side wall member a plurality of primary ridges extending longitudinally in the general direction of movement of said arc through said chute, at least some of the primary ridges having offset portions beginning at a point intermediate the ends of the arc chute to engage the opposite wall, a plurality of cooperating relatively short secondary ridges in the same general plane as the said some primary ridges extending inwardly from the opposite side wall member, and the offset portions extending over and engaging the secondary ridges to form a generally slotted plate construction.

4. A circuit interrupter including relatively movable contacts between which an arc may be formed upon opening the circuit, an insulating arc chute in which the arc is moved including spaced side wall members, each side wall member having on its side facing the other side wall member a plurality of primary ridges extending longitudinally in the general direction of movement of said arc through said chute, the primary ridges of one side wall member at least partially overlapping the primary ridges of the other side wall member, at least some of the primary ridges having offset portions to engage the opposite wall, and a plurality of cooperating secondary ridges in the same general plane as the said some primary ridges extending inwardly from the opposite side wall member.

5. A circuit interrupter including relatively movable contacts between which an arc may be formed upon opening the circuit, an insulating arc chute in which the arc is moved including spaced side wall members, each side wall member having on its side facing the other side wall member a plurality of primary ridges extending longitudinally in the general direction of movement of said arc through said chute, the primary ridges of one side wall member being staggered with respect to the primary ridges of the opposite wall member, at least some of the primary ridges having offset portions to engage the opposite wall, and a plurality of cooperating secondary ridges extending inwardly from the opposite side wall member and being in the same general plane as the said some primary ridges.

6. A circuit interrupter including relatively movable contacts between which an arc may be formed upon opening the circuit, an insulating arc chute in which the arc is moved including spaced side wall members, each side wall member having on its side facing the other side wall member a plurality of primary ridges extending longitudinally in the general direction of movement of said arc through said chute, the primary ridges of one wall being slightly spaced from, overlapping and staggered with respect to the primary ridges of the opposite wall so that the arc in passing through said chute is forced to take a tortuous closely confined path around the outer edges of portions of said primary ridges, at least some of the primary ridges having offset portions to engage the opposite wall, and a plurality of cooperating secondary ridges in the same general plane as the said some primary ridges extending inwardly from the opposite side wall member.

7. A circuit interrupter of the type wherein an arc is moved within an arc chute formed by the interleaving cooperation of a pair of spaced insulating side wall members each having a plurality of primary ridges extending inwardly therefrom, characterized by the fact that at least some of the primary ridges have offset portions and that between some of the primary ridges are secondary ridges of shorter length in the direction of arc travel, the secondary ridges being in substantially the same plane and mating with some of the primary ridges of the opposite wall member to form closed slot portions.

8. The method of making a side-wall member for an arc chute including the steps of: forming a blank of insulating material having a plurality of primary ridges with aligned deep and shallow valleys therebetween, running a pair of spaced cutters along the deep valley, and cutting into the two bottom corners of the shallow valley to form a second ridge of less height.
